UNITED STATES PATENT OFFICE.

CHARLES HORTON, OF NEW YORK, N. Y., ASSIGNOR OF ONE-TENTH TO AUGUSTUS M. HENRY, OF LARCHMONT, NEW YORK.

RADIOTELEGRAPHY.

1,174,726.

Specification of Letters Patent.

Patented Mar. 7, 1916.

Application filed July 29, 1913. Serial No. 781,853.

To all whom it may concern:

Be it known that I, CHARLES HORTON, a citizen of the United States of America, and resident of New York, borough of Brooklyn, county of Kings, and State of New York, (whose post-office address is No. 971 Putnam avenue, Brooklyn, New York,) have invented certain new and useful Improvements in Radiotelegraphy, of which the following is a specification.

This invention relates to improvements in wireless or radiotelegraphy, and more particularly aims to provide an improved coupler or oscillation transformer for rapidly and with precision establishing a highly accurate state of resonance or "tuning" agreement between the frequency of the circuit including the primary coil of the transformer at the receiving station and the frequency of the radio-electric waves intercepted by the receiving station's aerial.

One of the objects of this invention is to provide a coupler of the above type adapted for resonant adjustment within a wide range of wave lengths or frequency variations.

Another object is to provide such a coupler and one adapted for ease and rapidity of manipulation in establishing resonance.

Another object is to provide such a coupler and one that is capable of exceedingly simple and compact construction.

Another object is to provide such a coupler and one that is capable of inexpensive and economical manufacture.

Another object is to provide such a coupler and one wherein the primary and secondary coils of the transformer may be electrically coupled, and preferably by induction only, whereby there is obviated any danger of short-circuiting any of the coil-windings or otherwise accidentally interfering with the efficiency of the tuning.

An important object of this invention is totally to eliminate slider, switch or other imperfect contacts, and to substitute therefor permanent and low-resistance connections throughout.

Other objects and aims of the invention, more or less broad than those stated above,

together with the advantages inherent, will be in part obvious and in part specifically referred to in the course of the following description of the elements, combinations, arrangements of parts, and applications of principles constituting the invention; and the scope of protection contemplated will appear from the claims.

To these ends, my invention, whereof I disclose herein several of the various possible embodiments, generally consists in the novel arrangement, construction, and combination of parts as hereinafter more specifically set forth and described and particularly pointed out in the claims.

In the accompanying drawings, which are to be taken as a part of this specification, and wherein there are disclosed various possible embodiments of this invention as at present preferred: Figure 1 is a top plan view of one of said embodiments; Fig. 2 is a side elevation of the parts shown in Fig. 1; Fig. 3 is an end elevation, showing the parts disclosed in Figs. 1 and 2, and looking toward the left; Fig. 4 is a diagrammatic view of the windings carried by the cylinders 18 and 19 shown in Fig. 1, disclosing the winding 18' (carried by the cylinder 18) opposed in direction to the winding 19' (carried by the cylinder 19), which cylinders 18 and 19, adjustable with reference to each other as hereinafter described, are here assumed to carry, say, the primary coil of the transformer, the complete primary coil of the transformer being here thus comprised of the windings 18' and 19' arranged in series; Fig. 5 is a diagrammatic view of the windings carried by the cylinders 20 and 21 shown in Fig. 1, disclosing the winding 20' (carried by the cylinder 20) opposed in direction to the winding 21' (carried by the cylinder 21), which cylinders 20 and 21, adjustable with reference to each other as hereinafter described, are here assumed to carry, say, the secondary coil of the transformer, the complete secondary coil of the transformer being here thus comprised of the windings 20' and 21' arranged in series; Fig. 6 is a side elevation of another of said embodiments;

Fig. 7 is an end elevation of the parts shown in Fig. 6, and looking toward the left; Fig. 8 is a diagrammatic view of the windings carried by the disks 22 and 23 shown in Fig. 6, disclosing the winding 22' (carried by the disk 22) opposed in direction to the winding 23' (carried by the disk 23), which disks 22 and 23, adjustable with reference to each other as hereinafter described, are here 10 assumed to carry, say, the primary coil of the transformer, the complete primary coil of the transformer being here thus comprised of the windings 22' and 23' arranged in series; Fig. 9 is a diagrammatic view of 15 the windings carried by the disks 24 and 25 shown in Fig. 6, disclosing the winding 24' (carried by the disk 24) opposed in direction to the winding 25' (carried by the disk 25), which disks 24 and 25, adjustable 20 with reference to each other as hereinafter described, are here assumed to carry, say, the secondary coil of the transformer, the complete secondary coil of the transformer being here thus comprised of the windings 24' and 25' arranged in series; Fig. 10 is 25 a side elevation of another of said embodiments; Fig. 11 is an end elevation of the parts shown in Fig. 10, and looking toward the left; Fig. 12 is a side elevation of another of said embodiments; Fig. 13 is an end 30 elevation of the parts shown in Fig. 12, and looking toward the left; Fig. 14 is a side elevation of another of said embodiments; Fig. 15 is a detail view in elevation, showing certain parts and a method of mounting the same utilizable in connection with certain of said embodiments; Fig. 16 is a detail view in front elevation, showing the parts disclosed in Fig. 15; Fig. 17 is an enlarged detail view of certain of the parts 35 disclosed in Fig. 16; Fig. 18 is a diagrammatic view of the windings 18' and 19' of Fig. 4 (or 20' or 21' of Fig. 5, or 22' and 23' of Fig. 8, or 24' and 25' of Fig. 9), showing said windings not opposed in direction but still connected in series; Fig. 19 is a diagrammatic view of the windings 18' and 19' of Fig. 4 (or 20' and 21' of Fig. 5, or 22' and 23' of Fig. 8, or 24' and 25' of Fig. 40 9), showing said windings opposed in direction and connected in parallel; and Fig. 20 is a diagrammatic view of the windings 18' and 19' of Fig. 4 (or 20' and 21' of Fig. 5, or 22' and 23' of Fig. 8, or 24' and 25' of Fig. 55 9), showing said windings not opposed in direction and still connected in parallel.

Similar reference characters refer to similar parts throughout the several views of the drawings.

In the reception of wireless messages, the coupler or oscillation transformer plays a most important part. In fact, without this instrument, uninterrupted communication

with one particular station is almost impossible, as every train of waves traversing the effective zone of the antennae or the like produces its effect in the ears of the operator, with the result that his receiving instrument emits a confused medley of signals. 65 In other words, if of, say, two trains of waves traversing the zone of the aerial wire or antennae of the receiving station, one train of these waves has a certain number of oscillations per second and the other twice as 70 many, these two wave trains produce inharmonious alternating currents, each current corresponding in frequency to the number of oscillations characteristic of the appropriate train of waves. If the aerial, however, is 75 connected to an oscillation transformer, even of the types which have been proposed and utilized heretofore, a selection is possible. The oscillation transformer or coupler that is well-known in the art is merely 80 an arrangement of two independent circuits, one inductively adjustable with reference to the other and each adjustable as to self-inductance. Before taking up the description 85 of the present invention, then, it should be 90 understood that in utilizing a coupler, the primary and the secondary coils must be so adjusted that the natural frequency of the circuit including the primary coil and the antennae and the natural frequency of the 95 secondary circuit are each substantially the same as the frequency of the incoming waves which are intercepted by the aerial, for it is then (i. e. when these three frequencies 100 agree) that the greatest flow of current is produced in the secondary circuit, i. e., the circuit including, for the purposes of the present discussion, the receiving apparatus. When such a state of resonance is established, and the mutual inductance or 105 coupling is sufficiently weakened (as by widely separating the primary and the secondary coils), a train of waves coming from a particular sending station is isolated and made individually distinct from any signals from 110 other sending stations which, traversing the aerial simultaneously, would otherwise set up interference and conflict.

This invention comprises such an improvement over oscillating transformers or 115 couplers as heretofore proposed that it permits of absolutely accurate and continuous adjustment of the inductance of both the primary and secondary coils of the transformer at the receiving station, not only 120 with reference to the two coils as a combination, but with reference to each coil individually; so that the receiving apparatus may be easily and rapidly "tuned up" 125 to a particular wave frequency characteristic of a particular distant sending station with which it is desired to communicate. To vary the mutual inductance of the trans-

former by varying the relation of the two coils as a combination, I here illustratively arrange means for separating the coils in greater or less degree, since one well-known method of varying this mutual inductance consists in varying the position of one coil with respect to the other; and to vary the self-inductance of each coil individually I here illustratively arrange each coil so that certain of the windings of each coil may neutralize in varying degrees certain other windings of the same coil, as exemplified by the constructions of Figs. 1 to 9, inclusive, or illustratively arrange means for spacing certain of the windings of each coil in varying degrees from certain other windings of the same coil, as exemplified by the constructions of Figs. 10 to 17, inclusive.

Now referring particularly to Figs. 1 to 5 inclusive, the reference numeral 26 represents a suitable bed-plate adapted to carry as shown a pair of end standards 27, a center bracket 28, and a plurality of binding posts 29. Fixedly mounted within the bracket 28 is a cylinder 19 carrying a face-plate 30. Mounted as shown within this face-plate 30 are a pair of horizontally extending rods 31. A second cylinder 18 carries a face-plate 32 as shown, within which are fixedly mounted a plurality of transversely arranged sleeves 33, and these sleeves are adapted to coöperate in the manner disclosed with the rods 31 and the central rod 34 which extends longitudinally of the bed-plate 26 and is terminally mounted in the standards 27. It should be noted that the cylinders 18 and 19 are tubular, and that the cylinder 18 is of sufficiently greater diameter than the cylinder 19 to capacitate the former for travel longitudinally of the rods 31 and 34 to overlap and encompass in any desired degree said cylinder 19. A third cylinder 20 carries a face-plate 35 as shown, within which are mounted as illustrated a pair of horizontally extending rods 36 and a transversely arranged and centrally located sleeve 37. Sleeve 37 is adapted to coöperate in the manner disclosed with central rod 34 for the adjustment of cylinder 20 longitudinally of said rod. It should be noted that the bracket 28 is transversely apertured by means of the circular opening 38 as shown in Fig. 3, this opening being of a sufficiently large diameter to capacitate the cylinder 20 for travel longitudinally of the rod 34 to become overlapped by and enter in any desired degree the cylinder 19. A fourth cylinder 21 carries two end face-plates 38 and 39 as shown within each of which are fixedly mounted a plurality of transversely arranged sleeves 40, and these sleeves are adapted to coöperate in the manner disclosed with the rods 36 and the central rod 34. It should be

noted that the cylinder 20 is tubular, and that said cylinder is of sufficiently greater diameter than the cylinder 21 to capacitate the former for travel longitudinally of the rods 36 and 34 to overlap and encompass in any desired degree said cylinder 21.

The cylinder 18 carries in any suitable manner a predetermined number of turns of a winding (the winding 18' of Fig. 4) which forms a part of the primary coil of the transformer, and cylinder 19 carries in any suitable manner a predetermined number of turns of the winding (the winding 19' of Fig. 4) forming the remaining part of the primary coil of the transformer. From the diagrammatic disclosure of Fig. 4, it will be seen that the windings 18' and 19' are here arranged in series, but with the latter opposed in direction to the former. Suitable connecting conductors are shown at 41 in Fig. 4, and these conductors are preferably of sufficient length and flexibility to permit of as great an overlap of cylinder 19 by cylinder 18, without disintegrating the primary coil during the manipulation, as is desired. Cylinders 18 and 19, then, may be thought of as a plurality of relatively movable and separable supports for the unitary primary coil of the transformer.

The cylinder 20 carries in any suitable manner a predetermined number of turns of a winding (the winding 20' of Fig. 5) forming a part of the secondary coil of the transformer, and cylinder 21 carries in any suitable manner a predetermined number of turns of the winding (the winding 21' of Fig. 5) forming the remaining part of the secondary coil of the transformer. From the diagrammatic disclosure of Fig. 5, it will be seen that the windings 20' and 21' are arranged in series, but with the latter opposed in direction to the former. Suitable connecting conductors are shown at 42 in Fig. 5, and these conductors are preferably of sufficient length and flexibility to permit of as great an overlap of cylinder 21 by cylinder 20, or of cylinder 20 by cylinder 19, without disintegrating the secondary coil during the manipulation, as is desired. Cylinders 20 and 21, then, may be thought of as a plurality of relatively movable and separable supports for the unitary secondary coil of the transformer.

Having thus described this embodiment of this invention, the operation thereof, which should largely be obvious, may now be understood. The relatively movable elements of the coupler, that is, the cylinders 18, 20 and 21, are rapidly manipulated by the operator until they have been so slid upon rod 34 with relation to each other and with relation to the fixed cylinder 19 that the proper inductive combination is attained by the transformer to "tune up" the local

4

receiving apparatus to the frequency of the waves issuing from the distant sending station with which it is desired to communicate. The operator aforesaid first suitably varies 5 the self-inductance of each of the primary and secondary coils. One method of varying the inductance of a conducting coil, as is well-known, is to vary the effective number of turns therein; and in the present in- 10 stance this is accomplished in the case of the primary coil by adjusting the cylinder 18 to overlap in any degree the cylinder 19, for the winding on the cylinder 18 which overlaps the winding on the cylinder 19 is 15 opposite in direction to the winding on said cylinder 19 and therefore the overlapping turns neutralize each other and themselves have no inductive effect, and thus vary the self-inductance of the entire primary coil; 20 and in the case of the secondary coil by adjusting the cylinder 20 to overlap in any degree the cylinder 21, for the winding on the cylinder 20 which overlaps the winding on the cylinder 21 is opposite in direction to 25 the winding on said cylinder 21 and therefore the overlapping turns neutralize each other and themselves have no inductive effect and thus vary the self-inductance of the entire secondary coil. Having adjusted, 30 in accordance with the foregoing principles, the self-inductance of the primary coil and the self-inductance of the secondary coil, the mutual inductance of the combination is next adjusted (in the present instance by 35 physically separating to the proper degree the adjusted primary coil and the adjusted secondary coil), to the end that the electrical connection between the primary and the secondary coils is so weakened that any current 40 in the antennæ not in resonance with both the primary and secondary circuits will be unable to produce any appreciable effect upon the secondary circuit.

Now referring particularly to Figs. 6 to 9 45 inclusive, it will be seen that the bed plate 26 and the standards 27 are provided. A central bracket 43 supports vertically a disk 23. A vertically-arranged disk 22 is fixedly mounted upon a horizontally extending rod 50 44, which rod is slidably supported within a sleeve 45 carried by the left-hand standard 27 and which rod carries at its other end a finger-piece 46. A vertically arranged disk 25 is fixedly mounted upon a horizontally 55 extending sleeve-rod 47, which sleeve-rod is slidably supported within a sleeve 48 carried by the right-hand standard 27 and which sleeve-rod carries at its other end a finger-piece 49. A vertically-arranged disk 24 is mounted upon a rod 50 slidably supported within sleeve-rod 47 and carrying at its other end a finger-piece 51. Disks 22 and 23 60 may be thought of as a plurality of movable supports for the primary coil of the trans-

former, and here one-half of said coil, to wit, the winding 22' shown in Fig. 8, is suitably carried by the disk 22, and the other half of said coil, to wit, the winding 23', shown in Fig. 8, is carried in any suitable manner by the disk 23; the windings 22' and 70 23' here being arranged in series and opposed in direction as disclosed. And the disks 24 and 25 may be thought of as a plurality of relatively movable supports for the secondary coil of the transformer, and here one-half of said coil, to wit, the winding 24' shown in Fig. 9, is suitably carried by the disk 24, and the other half of said coil, to wit, the winding 25' shown in Fig. 9, is carried in any suitable manner by the disk 80 25; the windings 24' and 25' here being arranged in series and opposed in direction as disclosed. The conductors 52 shown in Figs. 8 and 9 are preferably of a suitable length and flexibility to permit of the varying adjustments of disks 22, 24 and 25 below described. Having thus described this embodiment of this invention, the operation thereof, which should largely be obvious, may now be understood. The relatively 90 movable elements of the coupler, that is, the disks 22, 24 and 25, are rapidly manipulated by the operator's utilization of the finger-pieces 46, 49 and 51, until said disks have been so set with relation to each other 95 and with relation to the fixed disk 23 that the proper inductive combination is attained by the transformer to "tune up" the local receiving apparatus to the frequency of the waves issuing from the distant sending station with which it is desired to communicate. It will be seen here, too, that, as described in connection with the description of the operation of the embodiment of this invention disclosed in Figs. 1 to 5 inclusive, 100 not only is the inductance selectively variable by virtue of separating more or less the primary coil as a unit from the secondary coil as a unit (that is, by varying the separation of the two disks 24 and 25, as a group, 110 say, from the two disks 22 and 23 as a group), but also by more or less separating the windings of each coil (that is, by varying the separation of the disk 22 from the disk 23, and by varying the separation of 115 the disk 25 from the disk 24).

Referring now particularly to the embodiment disclosed in Figs. 10 and 11, a base 53 is provided with a pair of standards 54 adapted to support as shown a fixed 120 shaft 55. Base 53 supports a transverse vertical plate 56, within which plate is fixedly carried as shown a winding-supporting disk 57. Similar disks 58, 59 and 60 are fixedly supported each terminally as shown of a separate arm 61. Each arm 61 is here an integral part of a separate bell-crank lever, the other arm of each of which bell-

crank levers is established by an arm 62 terminally carrying a finger-piece 63, and each of which bell-crank levers carries as shown a hub-portion adapted to be loosely 5 sleeved about the fixed shaft 55; from which it will be seen that by manipulating the finger-pieces 63 as desired the winding-supporting disks may be variously adjusted to overlap each other in a possible multi- 10 tude of combinations. An expansile spring 64, coiled about the shaft 55, and restrained at one end against a sleeve 65 loosely carried by the shaft 55, serves to maintain the said hub-portions of said bell-crank levers 15 in proper frictional engagement to secure their retention of any location to which they may have been shifted by the operator. An auxiliary base 66 is also shown, this base being here provided with the undercut slot 20 67 as shown. A presser-plate 68 carries a depending stem 69 which is mounted within said base 66 as shown, and to the lower end of this stem is pivotally connected one end of a bell-crank lever 70, this lever 70 being 25 intermediately pivoted as at 71 to the lip 72 carried by said base 66. The so-called bell-crank lever 70 is really, as illustrated in Fig. 10, a crank shaft arrangement, the rotatable rod 71 fixedly carrying at different 30 points in its length the two arms of the bell-crank lever 70. A lever 73 is fixedly pivoted upon the base 53 as shown, and is bifurcated at each end, one bifurcation to coöperate with the pin 74 carried by the 35 sleeve 65 and the other bifurcation to co-operate with the pin 75 carried by the short arm of the bell-crank lever 70. An expansile spring 76 is here coiled about the stem 69 and interposed between the presser-plate 40 68 and the base 66 as illustrated. A retractile spring 77 connects as shown the plate 56 and the disk 60, as an exemplification of a possible utilization of springs or counter-weights for compensation purposes. The 45 disk 58 here may carry in any suitable manner a predetermined number of turns of a winding similar to the winding 22' of Fig. 8, and the disk 59 may carry in any suitable manner a predetermined number 50 of turns of a winding similar to the winding 23' of Fig. 8, the winding upon disk 58 being preferably suitably flexibly connected to the winding upon disk 59 adjacent the location of the connector 52 shown in 55 Fig. 8, whereby disks 58 and 59, although relatively movable, coöperate to support the complete primary coil of the transformer. The disk 57 here may carry in any suitable manner a predetermined number of turns 60 of a winding similar to the winding 24' of Fig. 9, and the disk 60 may carry in any suitable manner a predetermined number of turns of a winding similar to the winding 25' of Fig. 9, the winding upon disk 57 be-

ing preferably suitably flexibly connected 65 to the winding upon disk 60 and the windings upon disks 57 and 60 being similarly connected to the adjacent conductors in the circuit as via the conductors 52 shown in Fig. 9, whereby disks 57 and 60, although 70 relatively movable, coöperate to support the complete secondary coil of the transformer. Having thus described this embodiment of this invention, the operation thereof, which should largely be obvious, may now be understood. The relatively movable elements of the coupler, that is, the disks 58, 59 and 60 are rapidly manipulated by the operator's utilization of the finger-pieces 63. Preliminarily to this manipulation, the operator rests the palm of his hand upon presser-plate 68, and thereby, through the rocking of the bell-crank lever 70 and the lever 73, moves the sleeve 65 to the right and compresses the spring 64 and thus 80 releases the frictional engagement normally maintained between the hub-portions carried by the disk-supporting bell-crank levers; and easy manipulation of the finger-pieces 63 is then made possible. Upon the 85 operator setting the disks 58, 59 and 60 so that they overlap each other and the fixed disk 57 in the proper degrees and relations to set up within the transformer the inductive combination requisite to accurately 90 "tune up" as desired, a release of the pressure of the operator's palm upon the presser-plate 68 immediately frictionally locks each of the disks 58, 59 and 60 into its properly 95 adjusted location. It will be seen here, too, 100 that, as described in connection with the description of the operation of the embodiments of this invention disclosed in Figs. 1 to 5 inclusive, not only is the inductance selectively variable by virtue of separating 105 more or less the primary coil as a unit from the secondary coil as a unit (that is, by varying the separation of the two disks 58 and 59 as a group, say, from the two disks 57 and 60 as a group), but also by more or 110 less separating the windings of each coil (that is, by varying the separation of the disk 58 from the disk 59, and by varying the separation of the disk 60 from the disk 57). 115

Now referring particularly to Figs. 12 and 13, it will be seen that the bed-plate 26 is again provided, and that said bed-plate integrally carries as shown the pair of side standards 27. These standards integrally carry a vertically and transversely supported plate 78. Plate 78 supports as shown a fixed winding-supporting disk 79. Similar disks 80, 81 and 82 are each fixedly supported by a separate arm 83 as shown. Each arm 83 is here an integral part of a separate bell-crank lever, the other arm of which bell-crank lever is established by an 120 125

6

arm 84 terminally carrying a finger-piece 85, and each of which bell-crank levers carries as shown a hub-portion adapted to be loosely sleeved about the fixed shaft 86; from which it will be seen that by manipulating the finger-pieces 85 as desired the winding-supporting disks may be variously adjusted to overlap each other in a possible multitude of combinations. An expansile spring 87, 10 coiled about the shaft 86, and restrained at one end against the right-hand standard 27 and at its other end against the sleeve 88 loosely carried by the shaft 86, serves to maintain the said hub-portions of said bell-crank levers in proper frictional engagement to secure their retention of any location to which they may have been shifted by the operator. A retractile spring 89 connects as shown the arm 83 and the plate 78, 15 as an exemplification of a possible utilization of springs or counter-weights for compensation purposes. Parts analogous to the auxiliary base 66 and its associated parts shown in Figs. 10 and 11, are not disclosed 20 in connection with this embodiment of this invention, but it should be understood that said base and its said associated parts, or an equivalent or substitute device or devices, could be within the scope of this invention 25 utilized in connection with any of the various possible embodiments thereof. The disk 80 here may carry in any suitable manner a predetermined number of turns of a winding similar to the winding 22' of Fig. 8, and 30 the disk 81 may carry in any suitable manner a predetermined number of turns of a winding similar to the winding 23' of Fig. 8, the winding upon disk 80 being preferably suitably connected to the winding upon 35 disk 81 adjacent the location of the connector 52 shown in Fig. 8, whereby disks 80 and 81, although relatively movable, coöperate to support the complete primary coil of the transformer. The disk 79 here may 40 carry in any suitable manner a predetermined number of turns of a winding similar to the winding 24' of Fig. 9, and the disk 82 may carry in any suitable manner a predetermined number of turns of a winding 45 similar to the winding 25' of Fig. 9, the winding upon disk 79 being preferably suitably flexibly connected to the winding upon disk 82 and the windings upon disks 79 and 82 being similarly connected to the adjacent 50 conductors in the circuit as via the connectors 52 shown in Fig. 9, whereby disks 79 and 82, although relatively movable, coöperate to support the complete secondary coil of the transformer. Having thus described this 55 embodiment of this invention, the operation thereof, which should largely be obvious, may now be understood. The relatively movable elements of the coupler, that is, the disks 80, 81 and 82 are rapidly manipulated 60 by the operator's utilization of the finger-pieces 85. Upon the operator setting said disks 80, 81 and 82 so that they overlap each other and the fixed disk 79 in the proper degrees and relations to set up within the transformer the inductive combination requisite to accurately "tune up" as desired, it will be seen here, too, that, as described in connection with the description of the operation of the embodiment of this invention disclosed in Figs. 1 to 5 inclusive, not only 65 is the inductance selectively variable by virtue of separating more or less the primary coil as a unit from the secondary coil as a unit (that is, by varying the separation of the two disks 80 and 81 as a group, say, 70 from the two disks 79 and 82 as a group), but also by more or less separating the windings of each coil (that is, by varying the separation of the disk 80 from the disk 81 75 and by varying the separation of the disk 82 from the disk 79). 80

Referring now particularly to the embodiment disclosed in Fig. 14, it will be observed that there are disclosed the bed-plate 26, the standards 27, the bracket 28, the supporting rod 34, the rods 31 and 36, the fixed cylinder 19, and the movable cylinders 18, 20 and 21. In this embodiment, for purposes of illustration, the cylinders 18 and 19 are assumed to carry the windings 18' and 19' 90 respectively, as illustrated in Fig. 4, and as described in connection with the embodiments of this invention illustrated in Figs. 1 to 5 inclusive, and the cylinders 20 and 21 are assumed to carry the windings 20' and 21' 95 respectively, as illustrated in Fig. 5, and as described in connection with the embodiment of this invention illustrated in Figs. 1 to 5 inclusive. Bed-plate 26 has 100 suitably mounted in the extension 90 thereof a suitable shaft 91 adapted to pivotally support the bell-crank levers 92, 93 and 94. Each bell-crank lever carries as shown a finger-piece 95. Bell-crank lever 92 is pivotally connected as shown to one end of a link 105 96, the other end of which link is fastened as shown to movable cylinder 18, said link being preferably of a suitable flexible material. A similar link 97 similarly connects bell-crank lever 93 and movable cylinder 20, and a similar link 98 similarly connects bell-crank lever 94 and movable cylinder 21. Retractile springs 99 connect as shown, 110 one the left-hand standard and the cylinder 18, another the bracket 28 and cylinder 20, and the other cylinders 20 and 21, as an exemplification of a possible utilization of springs or counterweights for compensation purposes. Having thus described this embodiment of this invention, the operation 115 thereof, which should largely be obvious, may now be understood. The relatively movable elements of the coupler, that is, the 120 disks 80, 81 and 82 are rapidly manipulated 125

cylinders 18, 20 and 21, are rapidly manipulated in a manner similar to the hereinbefore described manipulation of the cylinders 18, 20 and 21 shown in Figs. 1 and 2, but by the operator's utilization of the finger-pieces 95, to the end that said cylinders 18, 20 and 21 overlap each other and the fixed cylinder 19 in the proper degrees and relations to set up within the transformer the inductive combination requisite to accurately "tune up" as desired.

Referring now particularly to Figs. 15, 16 and 17, there is disclosed an alternative method of mounting the finger-pieces 95 shown in Fig. 14 wherein a presser-plate or the like similar to the presser-plate 68 shown in Fig. 10 may be utilized to release a clutch, rather than a frictional, engagement between the bell-crank levers which, mounted upon a suitable shaft 100 mounted in suitable standards 101, carry the finger-pieces 95. This is here illustratively accomplished by providing an auxiliary shaft 102, mounted within said standards 101 as shown, and adapted for the sleeving slidably thereon of an extension 103 carried integrally by a clutch member 104 slidably sleeved on shaft 100. As shown best in Fig. 16, a clutch member 104 is interposed to the right of each of the bell-crank levers 94, 93 and 92. The adjacent end faces of each bell-crank lever and the clutch member to the right thereof are provided with engaging teeth as shown and as referred to by the reference numeral 105 in Fig. 17. It will be observed that with a bell-crank lever out of engagement with its co-operating clutch member 104, said bell-crank lever is capable of rocking upon its shaft 100, but that said clutch member 104, while capacitated for sliding bodily away from said bell-crank lever to disengage its clutch, is yet restrained from any rotation about the shaft 100, but is, on the contrary, keyed in place by the sleeving engagement of its extension 103 with the shaft 102. An expansile spring 106 is coiled about the shaft 102 as shown and tends to maintain each clutch member 104 in normal clutch engagement with its proper bell-crank lever and thereby prevent any manipulation of said finger-pieces 95 until the operation of suitable releasing means, and to lock any or all of said cylinders 18, 20 and 21 in their then adjusted position or positions upon said releasing means becoming ineffective.

It will thus be seen that there has been provided an improved coupler or oscillation transformer for accomplishing the various ends and objects above stated, and one that is particularly capacitated for rapidity and precision in attaining a state of resonance; and that an important step forward has been disclosed which is resident in the fact that

all slider, switch or other movable and imperfect contacts are dispensed with. While this is accomplished here in part by mounting the complete primary coil of the transformer so that various windings forming parts of the unitary primary coil are each mounted upon a separate support one of which is movable with relation to the other, and also by mounting the complete secondary coil of the transformer so that various windings thereof forming parts of the unitary secondary coil are each mounted upon a separate support one of which is movable with relation to the other, it should be understood that the disclosures herein are merely illustrative of the general theory of this invention, and that while throughout the embodiments one winding of either a primary or a secondary coil is assumed to be so manipulated with reference to another winding of said coil as to vary the self-inductance of the coil by neutralizing the inductive effect of turns of either or both of said windings, any other method of varying the self-inductance of a coil of a transformer during the maintenance of said coil's initial and permanent current-conducting characteristic is contemplated, and that, while the neutralization, as aforesaid, of certain of the turns of either the primary or secondary coil has been illustratively disclosed in Figs. 4, 5, 8 and 9 as having been accomplished by arranging the two illustrated windings of either a primary or a secondary coil as opposed in direction but connected in series, it should also be understood that this same neutralization operation may be accomplished by arranging said windings still connected in series but not opposed in direction as shown in Fig. 18, or by arranging said windings opposed in direction but connected in parallel, as shown in Fig. 19, or by arranging said windings in parallel and not opposed in direction, as shown in Fig. 20. It should be further understood that while the embodiments herein disclosed have been described in connection with their utilization as a receiving instrument, it is obvious that they can with great advantage be utilized for sending.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense. It is also to be understood that the language used in the following claims is intended to cover all the generic and specific features of the invention herein described and all statements of the scope of the invention which, as a matter

of language, might be said to fall there-between.

Having described this invention, what I claim as new, and desire to secure by Letters 5 Patent, is:

1. In a device of the class described, a primary coil including a plurality of relatively movable sub-divisions and a fixed sub-division and each sub-division including a 10 plurality of windings, and a secondary coil including a plurality of relatively movable sub-divisions and each sub-division including a plurality of windings, each of said sub-divisions being separately and independently movable relatively of said fixed 15 sub-division.

2. In a device of the class described, a primary coil including a plurality of sub-divisions and each sub-division including a 20 plurality of windings, a secondary coil including a plurality of sub-divisions and each sub-division including a plurality of windings, and means adapted independently to vary the individual location of merely any 25 one of three of said sub-divisions relatively of the location of a fourth.

3. In a device of the class described, a primary coil including a plurality of relatively movable sub-divisions and each sub-division including a plurality of helicoidal windings, and a secondary coil including a 30 plurality of relatively movable sub-divisions and each sub-division including a plurality of helicoidal windings, one of said sub-divisions being mounted on a fixed support and three of said sub-divisions being separately and independently movable relatively of 35 said fixed support.

4. In a device of the class described, a primary coil including a plurality of relatively movable sub-divisions and each sub-division including a plurality of helicoidal windings, and a secondary coil including a 40 plurality of relatively movable sub-divisions and each sub-division including a plurality of helicoidal windings, one of said sub-divisions being mounted on a fixed support and three of said sub-divisions being separately and independently movable relatively of 45 said fixed support; each of said sub-divisions being carried on a separate tubular support.

5. In a device of the class described, a primary coil including a plurality of relatively movable sub-divisions and each sub-division including a plurality of helicoidal windings, and a secondary coil including a 55 plurality of relatively movable sub-divisions and each sub-division including a plurality of helicoidal windings, one of said sub-divisions being mounted on a fixed support and three of said sub-divisions being separately and independently movable relatively of 60 said fixed support; each of said sub-divisions

being carried on the outer cylindrical surface of a separate tubular support.

6. In a device of the class described, a primary coil including a plurality of relatively movable sub-divisions and each sub-division including a plurality of helicoidal windings, and a secondary coil including a 70 plurality of relatively movable sub-divisions and each sub-division including a plurality of helicoidal windings, one of said sub-divisions being mounted on a fixed support and three of said sub-divisions being separately 75 and independently movable relatively of said fixed support; each of said sub-divisions being carried on a separate tubular support, and one of said supports being of such an inner diameter that there may be telescoped 80 within the same the three other supports, one of said three supports being of such an inner diameter that there may be telescoped therein the two other supports, and one of said two supports being of such a diameter 85 that there may be telescoped therein the fourth support.

7. In a device of the class described, a primary coil including a plurality of relatively movable sub-divisions and each sub-division including a plurality of helicoidal windings, and a secondary coil including a 90 plurality of relatively movable sub-divisions and each sub-division including a plurality of helicoidal windings, one of said sub-divisions being mounted on a fixed support and three of said sub-divisions being separately and independently movable relatively of 95 said fixed support; each of said sub-divisions being carried on a separate tubular member, and one of said supports being of such an inner diameter that there may be telescoped within the same the three other supports, one of said three supports being of such an inner diameter that there may be 100 telescoped therein the two other supports; and one of said two supports being of such a diameter that there may be telescoped therein the fourth support; and means for separately and independently moving any one of 105 said movable sub-divisions and its support relatively of said fixed sub-division and its support, said means including a plurality of instrumentalities each manipulable by a finger of the operator.

8. In a device of the class described, in combination, a support having a spiral inductance wound thereon, a second support having a spiral inductance wound thereon, a third support having a spiral inductance 110 wound thereon and a fourth support having a spiral inductance thereon, two of said supports each carrying a sub-division of a primary coil and two other of said supports each carrying a sub-division of a secondary 115 coil, one of said supports being fixed and

three of said supports being separately and independently movable relatively of said fixed support.

9. In a device of the class described, in combination, a support having a cylindrical-spiral inductance wound thereon, a second support having a cylindrical spiral-inductance wound thereon; a third support having a cylindrical spiral-inductance wound thereon and a fourth support having a cylindrical spiral-inductance wound thereon, two of said supports each carrying a sub-division

of a primary coil and two other of said supports each carrying a sub-division of a secondary coil, one of said supports being fixed 15 and three of said supports being separately and independently movable relatively of said fixed support.

In witness whereof I have hereunto signed my name in the presence of two witnesses.

CHARLES HORTON.
